UNITED STATES PATENT OFFICE.

JOHN W. BERNBAUM, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CARLINE CONSTRUCTION.

Application filed June 1, 1920. Serial No. 385,459.

To all whom it may concern:

Be it known that I, JOHN W. BERNBAUM, a citizen of the United States, residing in Chicago, in the county of Cook and State 5 of Illinois, have invented a new and useful Improvement in Carline Constructions, of which the following is a specification.

This invention relates to carline constructions; such as are more particularly designed 10 for use in freight car roof frames; the invention has for an object the provision of a simply constructed well-balanced carline that is not only strongly braced in its middle portion, but also is especially reinforced at 15 the points of attachment to the side frame members or side plates, with the result that the carline, as a whole, is stiffened and made especially resistant at the points where vertical, horizontal and torsional stresses are 20 most likely to occur.

In addition to the general object recited above, the invention includes among its objects such other improvements and advantages in construction and operation as are 25 found to obtain in the structures and devices hereinafter described or claimed.

In the accompanying drawings, forming a part of this specification, and showing, for purposes of exemplification, a preferred 30 form and manner in which the invention may be embodied and practiced, but without limiting the claimed invention specifically to such illustrative instance or instances:

Figure 1 is a plan view of a portion of a 35 car roof frame provided with a carline constructed in accordance with the present improvements;

Fig. 2 is a transverse section through the car roof, showing the carline in longitudinal 40 elevation;

Fig. 3 is an enlarged fragmentary view of the end portion of the carline adjacent to the side plate and showing the mode of attachment thereto;

Fig. 4 is an enlarged vertical section on the line 4-4 of Fig. 2;

Fig. 5 is a perspective of the end of the carline and of the top reinforcing plate.

Fig. 6 is a plan view of a portion of one 50 side of a car roof frame, illustrating a modification;

Fig. 7 is a transverse section through the car roof illustrated in Fig. 6, showing the carline in longitudinal elevation;

Fig. 8 is an enlarged vertical section on 55 the line 8-8 of Fig. 7; and

Fig. 9 is an enlarged vertical section on the line 9-9 of Fig. 7.

The same characters of reference indicate the same parts throughout the several views 60 of the drawings.

In both forms of the invention shown, the carline 21 consists of a single steel bar, of channel or U-shape in cross section, comprising the web 22 of U or channel cross section and lateral flanges 23, bent oppositely from the top edges of the opposite side members of the web. As shown, the web 22 is downwardly inclined or tapered from the middle portion of the carline to the opposite ends thereof, at the angle adapted to impart the desired pitch to the roof; and, preferably, said web gradually diminishes in depth from its middle portion or horizontal portion 24 of the lateral flanges 23, to the opposite ends of the carline. The channel or web 22 is preferably of uniform or constant width from end to end of the carline. In order to compensate for the excess of metal in the middle portion of the 75 channel or web, with respect to the end portions thereof and to equalize the distribution of metal throughout the length of the carline, the lateral flanges 23 are tapered and gradually increase in width from the 80 middle or apex of the carline to its opposite ends, the increase in metal in the lateral flanges towards the ends being proportionate to the decrease in metal in the web.

At the opposite ends of the web 22 and 90 lateral flanges 23, the carline is formed with down-turned vertical flanges 25. The opposite ends of the carline are secured to the side frame members, such as the side plates 26 of the car roof frame, and in order to 95 strengthen the parts at the points of attachment of the carline to said side plates, there are provided top or reinforcing plates 27 in the form of angle plates having lateral webs 28 adapted to overlie and be secured 100 by bolts 29 to the end portions of the lateral flanges 23 and vertical webs 30 adapted to rest against the outer faces of the down-turned flanges 25 at the opposite ends of the carline. As shown in Figs. 2 and 3, the 105 vertical webs 30 of the top plates are interposed between the down-turned flanges 25 and the inner faces of the side plates 26,

and the opposite ends of the carline are secured to said side plates by bolts 31 respectively located on opposite sides of the channel or web 22 and passed through the 5 down-turned flanges 25, the vertical webs 30 of the top plates, and the side plates 26.

In the form of the invention illustrated in Figs. 6 to 9 inclusive, the side plates 26 are reinforced by angle bars 32 extending 10 along with the side plates and having horizontal webs 33 beneath the bottom faces of the side plates and vertical webs 34 interposed between the vertical webs 30 of the top plates 27 and the inner faces of the side 15 plates. The bolts 31 for securing the carline to the side plates are passed through the vertical webs 34 of the reinforcing angle bars 32, as well as the down-turned flanges 25 of the carline, the vertical webs 30 of 20 the top plates, and the side plates 26.

The carline illustrated in the drawings may support in the usual way the ridge pole 35, and the purlins 36, these being bolted to the lateral flanges 23 of the carline.

25 The invention as hereinabove set forth is embodied in a particular form of construction but may be variously embodied within the scope of the claims hereinafter made.

30 I claim:

1. In a carline construction, the combination with the side plates of a car roof frame; of a carline embodying a single steel bar formed with a web of channel section and of 35 uniform width from end to end of the carline but gradually decreasing in depth from the middle portion to the opposite end portions of the carline, with lateral flanges bent outwardly from the side members of said 40 web and gradually increasing in width from the middle portion to the end portions of the carline, and with down-turned flanges

at the opposite ends of the carline; reinforcing plates of angle-formation positioned with their lateral webs secured to the lateral 45 flanges of the carline and with their vertical webs resting against the outer faces of the aforesaid down-turned flanges; and bolts passed through the down-turned flanges, the vertical webs of the reinforcing members and the side plates, for securing the carline to the side plates; substantially as specified.

2. In a carline construction, the combination with the side plates of a car roof frame; of a carline embodying a single steel bar 55 formed with a depending web of channel section, with lateral flanges bent outwardly from the top of the side members of said web, and with down-turned flanges at the opposite ends of the carline; reinforcing 60 members having portions overlying the end portions of the lateral flanges and engaging the outer faces of the down-turned flanges; and means for securing the down-turned flanges and the reinforcing members to the 65 side plates; substantially as specified.

3. In a carline construction, the combination with the side plates of a car roof frame; of angle bars positioned with their vertical and horizontal webs respectively engaging 70 the inner side and bottom faces of the side plates; a carline embodying a single steel bar formed with a web of channel section, with lateral flanges bent outwardly from the side members of said web, and with 75 down-turned flanges at the opposite ends of the carline; top plates having portions overlying the end portions of the lateral flanges and engaging the outer faces of the down-turned flanges; and means for securing the down-turned flanges, and the top 80 plates to the reinforcing bars and the side plates; substantially as specified.

JOHN W. BERNBAUM.
